UNITED STATES PATENT OFFICE.

ERAZM. J. JERZMANOWSKI, OF NEW YORK, N. Y.

PROCESS OF PRODUCING GAS.

SPECIFICATION forming part of Letters Patent No. 333,860, dated January 5, 1886.

Application filed April 7, 1885. Serial No. 161,466. (No specimens.)

To all whom it may concern:

Be it known that I, ERAZM. J. JERZMANOWSKI, of the city, county, and State of New York, have invented a new and useful Improvement in Processes of Producing Gas, of which the following is a full, true, and exact description, reference being had to the accompanying drawings.

The improved process which I shall proceed to describe is one in which the resulting gas is produced by the combined action of coal and lime upon steam and upon steam carrying petroleum or other hydrocarbon, as will be readily understood from the accompanying drawings.

The process consists, generally, in the use of two separate chambers, one containing lime and the other coal, by preference anthracite, so connected that the products of combustion of the coal are used, by preference, with an additional supply of air in heating the lime to the requisite temperature for making the conversions hereinafter to be described, while the heated body of the coal and the lime unite together in producing the gas, which may or may not be afterward enriched in the well-known way. In order to accomplish this interaction of coal and lime, I cause steam to pass through the body of the coal, thereby making what is commonly known as "water-gas," and then unite with this an additional quantity of steam carrying a hydrocarbon in suspension. The said gas is caused to pass through a body of hot lime, thereby converting the steam and hydrocarbon into hydrogen, and, perhaps, a certain amount of carbonic acid, or carbonic acid and carbonic oxide.

In the accompanying drawings similar letters refer to similar parts.

Figure 1 is a vertical elevation of my apparatus, and Fig. 2 is a top view of the same. Fig. 3 is a vertical elevation on the opposite side from Fig. 1. Fig. 4 is an end elevation showing some of the pipe-connections. Fig. 5 is a vertical transverse section through Fig. 1. Fig. 6 is a section through Fig. 2 on the line *yy*, the position of the apparatus as shown, however, being reversed.

My apparatus consists, generally, in an external casing, A. Within this are two chambers, B and C. It is obvious that these cham-

bers need not be in the same external structure, though I prefer to have them so for convenience and the saving of heat. These chambers are separated from each other by the partition L, except at the top of said partition, where they communicate with each other through the passage R. Each chamber may be provided with an upper opening at P P', as shown, which are suitably closed by means of sand seals. Through these openings the chambers are charged.

In the chamber B are likewise the openings b f, above the grate-bars S, whereby the chambers are readily discharged when desired.

In chamber N, beneath the grate-bars and beneath the chamber B, are ash-doors *a* and *b*. These doors are placed upon small chambers extending out somewhat from the main structure, and into their tops are the pipe-connections hereinafter to be described.

Beneath the grate-bars S of the chamber C are the doors *c* and *g*, for removing any lime which may fall through the grate-bars.

Toward the upper part of the chamber C, on one side are the open rings *k* *k*, communicating with the steam and naphtha pipe hereinafter to be described. In the opposite wall, likewise toward the top, are the openings *g* *g*, communicating with air-pipe F, hereinafter to be described. The chamber O, beneath the grate-bars S, communicates with the large pipe or chimney D. The upper end of this is closed by a suitable valve, E, which is controlled by a wheel and chain, *p*, as will be readily seen.

Of course many other methods could be devised; but the one shown is very convenient, for by it the valve when opened can be thrown completely out of the range of the escaping gases. The pipe J likewise communicates with the hydraulic main M.

An air-pipe, F, is provided, through which air is forced by a blower or other suitable mechanism into the apparatus. This pipe has three branches, one communicating with the ash-door *h*, one communicating with the ash-door *a* beneath the chamber B, and the other communicating with the openings *g* *g* in the lime-chamber C. A steam-pipe, G, is likewise provided. One branch of this enters the ash-chamber below the chamber B at

l, as shown in Fig. 3. Another connection proceeds from this pipe *G* to the naphtha-injector *K*. Naphtha enters this injector through the pipe *r*. The combined steam and naphtha pass by the pipe *H* through the openings *k k* at the proper period of the operation.

Eye-holes *m* may be provided for observing the internal condition of the apparatus. Suitable valves are provided in all these pipes 10 and branches, which I will not here fully describe in detail, since they will be readily supplied by a competent gas-engineer.

The operation of my apparatus can now be readily understood. The chamber *C* is filled 15 or partly filled with lime in lumps by preference about three inches in diameter. A suitable supply of steam, hydrocarbon, such as petroleum, and compressed air is provided. Instead of naphtha or petroleum, I may use 20 some other liquid hydrocarbon, or even a finely-divided solid hydrocarbon carried by a liquid or otherwise injected into the apparatus. I prefer, however, to use in this operation ordinary petroleum, which is both cheap 25 and efficacious. The anthracite coal in chamber *B* having been kindled, air is allowed to enter through the branches of the pipe *F*, the quantity entering through the openings *g g* being by preference less than that entering 30 through the openings *a* and *h*. The effect of this is to thoroughly heat the coal and lime, for the products of combustion pass upward through the coal-bed, and through the passage *R* above the lime, where they meet an 35 additional supply of air, thereby completing the combustion. The highly-heated gases then pass downward through the lime in the chamber *C*, through the chamber *O*, chimney *D*, pipe *J*, and thence escape through the 40 purge-valve *E*, which is then open. When the lime has been heated to the proper temperature, the air-supply is cut off and the purge-valve *E* closed. Steam and naphtha are then injected through the pipe *H* and openings *k k*. These, passing downward together 45 through the lime-bed in the chamber *C*, become converted into an illuminating-gas of low candle-power, the candle-power depending in part upon the amount of petroleum 50 added. At the same time, by preference, I cause a jet of steam to enter beneath the coal-bed through the opening *l*. This passes upward through the coal-bed, and becomes converted into water-gas, and meets above the 55 lime, steam, and petroleum there injected, and the combined water-gas, steam, and petroleum pass downward through the body of

the lime. The resultant gas so produced is much superior in quality to water-gas containing a much less percentage of carbonic oxide, and if the process is properly managed it is itself an illuminating-gas of several candle-power. This gas is subsequently enriched, if it is to be used as an illuminating-gas, by a hydrocarbon in the usual way. 60 When the lime or coal has become so much cooled by this action as to cease to act efficaciously, the steam and naphtha are shut off, and air is again admitted.

By means of the alternate doors above the 70 grate-bars the apparatus is readily discharged in case of need, and the supply of coal and lime is readily kept up through the openings above.

The apparatus is complete and convenient, 75 and is not liable to injury or destruction.

I do not in this application claim the apparatus, as I intend to make a separate application therefor.

What I claim as my invention, and desire 80 to secure by Letters Patent, is—

1. The process herein described of making a combustible gas, which consists in first making water-gas by injecting steam through an incandescent body of carbon, in then adding 85 to said water-gas steam and hydrocarbon, and in passing the combined water-gas, steam, and hydrocarbon through a converting body of heated lime, substantially as described.

2. The process herein described of making 90 a combustible gas, which consists in first making water-gas by injecting steam through an incandescent body of carbon, in then adding to said water-gas steam and hydrocarbon, and in passing the combined water-gas, steam, and 95 hydrocarbon through a converting body of heated lime, and alternately heating the lime by the products of combustion of the carbon used in making the water-gas, substantially as described.

3. The mode of producing a combustible gas, consisting in combining hydrocarbon and steam with a water-gas, and then subjecting the said gas, steam, and hydrocarbon to the action of heated lime, substantially as de- 105 scribed.

In testimony whereof I have signed my name to this specification in the presence of two subscribing witnesses.

ERAZM. J. JERZMANOWSKI.
